UNITED STATES PATENT OFFICE.

RICHARD B. MARSH, OF PHILADELPHIA, PENNSYLVANIA, ASSIGNOR TO HALE AND KILBURN COMPANY, OF PHILADELPHIA, PENNSYLVANIA, A CORPORATION OF DELAWARE.

CAR-SEAT.

1,212,533.

Specification of Letters Patent. Patented Jan. 16, 1917.

Application filed August 10, 1915. Serial No. 44,674.

To all whom it may concern:

Be it known that I, RICHARD B. MARSH, a citizen of the United States, residing at Philadelphia, in the county of Philadelphia and State of Pennsylvania, have invented 5 certain new and useful Improvements in Car-Seats, of which the following is a specification.

My invention relates to improvements in 10 railway car seats of the type in which the back is movable across the seat and operates through suitable connections to rock the latter, when the back is reversed, to reverse the seating inclination of the seat-cushion.

15 My improvements have to do chiefly with the connections between the back and seat-cushions, improved results being attained by novel combinations and arrangements of elements. The back-supporting standards 20 carry rollers which are mounted on channel tracks, which latter, however, are not secured directly to the wall and aisle end plates, but are supported directly upon the cross rails, underneath the respective ends 25 of the seat-cushion. Also, the channel tracks referred to do not face inwardly, as they do in usual practice when secured to the inner faces of the end plates, but face outwardly. The result of this is that the 30 back-supporting standards pass closely adjacent to the ends of the seat-cushion with their rollers extending inwardly, beneath the seat-cushion into the channel tracks, the levers by which the seat-supporting rockers 35 are operated from the movements of the standards being located on the outer sides of the standards instead of on the inner sides as formerly. The result of the altered positioning of the elements referred to is that 40 the seat-cushion is given a maximum length in relation to the overall length of the seat, the construction permitting the seat-cushion to extend a greater distance toward the wall and aisle plates than has been possible with 45 mechanisms previously used. All mechanism is removed from the aisle and wall plates except the bearings for the rock-shaft by which the rockers are operated. Also, since practically no space remains between 50 the ends of the seat-cushion and the respective end plates, except that necessary for the movements of the standards, the danger of a passenger's clothing or the like, catching in the spaces referred to is greatly de- 55 creased.

In my preferred construction, tubular

cross rails are employed, to which the channel tracks are secured by means of small brackets, preferably drop forgings, mounted on the cross rails. Preferably, each rocker 60 is supported by a steel bracket riveted to the adjacent channel track. The channel track at the aisle end may be positioned substantially above the pedestal which supports that end of the cross rails; by this construction 65 the various strains on the rocker and standard are transmitted directly through the channel track, forged bracket, cross rails and pedestal, so that there is practically a straight line connection between the back 70 and the floor of the car. Therefore extreme strains on the cross rails, such as are produced when the pressure on the back is transmitted to the aisle plate and thence laterally along the connecting rails to the 75 pedestal, are eliminated. Another improved result of my construction consists in the fact that parts thereof may be made as a complete unit in the shop, viz., the track, the bracket on the track to which the rocker is 80 pivoted, the rocker itself, and the two brackets by which the track is secured to the cross rails. These various elements are combined in one unit, before shipping, the construction thus permitting improved shipping 85 conditions and a simple and economical assembly of the complete seat.

Other objects of my invention are the provision of improved portions of the mechanism, such as the rocker movement. 90

In order that a clearer understanding of my invention may be had, attention is hereby directed to the accompanying drawings forming part of this application and illustrating certain embodiments of my invention. 95

In the drawings, Figure 1 represents an end elevation of a seat, provided with my invention, Fig. 2 is a front elevation of the same, Fig. 3 is a vertical section taken on line 3—3 of Fig. 2, to an enlarged scale, Fig. 4 is a top plan view of the mechanism shown in Fig. 3, Fig. 5 is a longitudinal vertical section taken on line 5—5 of Fig. 3, Fig. 6 is an end elevation of a seat having a somewhat different rocker movement, Fig. 7 is a front elevation of the same, Fig. 8 is a cross-section on line 8—8 of Fig. 7, Fig. 9 is a top plan view corresponding to Fig. 8, and Fig. 10 is a longitudinal vertical section on line 10—10 of Fig. 6. 105 110 115

Referring first to Figs. 1 to 5 of the draw-

ings, the cross rails 1, 1, preferably tubular in cross-section, are illustrated in the drawings as supported at their inner ends by the wall plate 2 and adjacent to their outer ends 5 by the pedestal 3, it being obvious that a similar pedestal might be employed at the wall end of the seat if desired. The seat-cushion 4 is supported by rockers 5, 5, and back cushion 6 is supported by standards 10 7, 7 carrying rollers 8, 8 extending from the inner faces of the standards, and resting upon the lower flanges of the curved channel tracks 9, 9. An aisle end plate 10, similar to the wall end plate 2, is carried by the 15 outer ends of the tubular cross rails 1, 1. As stated, aisle end plate 10 does not support any of the mechanism, except the rock-shaft hereinafter referred to, and accordingly can be made quite light, being a mere 20 cover plate. Each channel track 9 is mounted with its top and bottom flanges faced outwardly, that is the track at the aisle end faces the aisle and the track at the wall end faces the wall, the tracks being located 25 beneath or partly beneath the respective ends of the seat-cushion 4. Each channel track 9 is supported by a pair of brackets 11, 11 from the cross rails 1, 1, these brackets preferably being drop forgings, each having a 30 vertical web portion riveted or otherwise secured to the vertical web 9' of the channel track. Each bracket is provided with a horizontally curved bearing portion 11' which rests upon a cross rail 1, these bearing portions 11' being secured to the cross rails by means of bolts 12.

Preferably, each rocker 5 is supported by a pressed steel bracket 13, which is provided with a central portion 13' of channel 40 shape riveted to the web 9' of the channel track, as shown at 14. Bracket 13 is provided with an upwardly extending portion 13² above the channel shaped portion 13', and an upwardly extending portion 5' of 45 the rocker is pivoted thereto by a pin 15, the portions 5' and 13² of the rocker and bracket extending upwardly in a space or slot in the frame of the seat-cushion, this 50 space suitably being a space between the cross slats of the seat-cushion frame. By this means a pivotal point is provided for the rocker at a considerable distance above the bottom edge of the seat cushion.

The rocker is preferably operated by eccentric means. As illustrated, a rock-shaft 16 is rotatably supported in the bearings formed on the two end plates and a pair of eccentrics 17, 17 are secured thereon. Each eccentric is rotatably mounted within the 55 jaws 5² of its rocker. A lever 18 has a boss 18' secured to rock-shaft 16, lever 18 having at its upper end a pin 19 adapted to play in the slot 20 of standard 7. It is evident that the rockers and seat-cushion are held 60 in position by the engagement of eccentric

17 in the rocker and the connection therefrom to the standard when the back is in one of its positions of rest, and that the eccentrics, and accordingly the rockers, will be rocked when the back is reversed, the eccentrics moving around the rock-shaft to reverse the seating inclination of the seat.

It may be noted that levers 18 are positioned on the outer sides of the standards within the flanges, such as 10', of the end plates, the pins 19 therefor extending inwardly from the levers into the slots in the standards, as also the rollers 8 extend inwardly from the standards into the channel tracks, the word "inwardly" being understood as signifying the direction from either end of the seat lengthwise thereof, toward the central portion of the seat-cushion, and the word "outwardly" the reverse. By the arrangement described, the seat-cushion is permitted to extend outwardly some distance beyond the back-cushion into close proximity to the standards 7 which move closely adjacent to the end plates, it being understood that the standards are outwardly offset in the usual manner to permit the same to clear the ends of the seat cushion. Each channel track 9, together with its supporting brackets 11, the rocker supporting bracket 13, together with its rocker 5, may be assembled together in the manufacturing establishment as a unitary construction as stated.

The construction illustrated in Figs. 6 to 10 inclusive differs from that already explained chiefly in the use of a different form of rocker. Each rocker 5^A is arranged to have its bearing on the tubular rails 1, 1, the lower surfaces of each rocker being formed with a compound curve comprising lower bearing portions 5^{A'} and upper bearing portions 5^{A2}. The eccentrics 17^A are secured upon rock-shaft 16, within the jaws of the rockers, and connected by levers 18 with the standards 7, in the same manner as described in connection with the first species of my invention. When the back is in one end position, the rockers rest, with surfaces 5^{A'} at one end and surfaces 5^{A2} at the other end contacting the cross rails, the rockers sliding to the reversed position when the eccentrics are operated by the reversal of the back.

It is obvious that my invention is not limited strictly to the exact details of construction described herein, but is as broad as is indicated in the appended claims.

Having described my invention, what I claim as new therein and desire to secure by Letters Patent of the United States is:—

1. In a car-seat, the combination of a pair of cross rails, an end plate secured to the aisle ends of the same, a curved track supported on said rails, facing outwardly, and spaced inwardly from said plate, a back-

supporting standard extending between said plate and track, having bearing means therefor mounted on said track, a seat-cushion extending above said track, a rocker supporting said seat, and means for operating said rocker, comprising a lever connected to said standard, and extending between said standard and end plate, substantially as set forth.

2. In a car-seat, the combination of a pair of cross rails, means for supporting the same, comprising a pedestal spaced inwardly from the aisle end of said rails, an aisle end plate secured to the ends of said rails, brackets secured on said rails substantially above said pedestal, a curved track secured on said brackets, a back-supporting standard extending between said plate and track, having supporting means therefor extending inwardly therefrom, movably mounted on said track, a seat-cushion extending over said track into close proximity to said standard, rocker means supporting the same supported from said cross rails above said pedestal, and operating connections between said rocker means and standard, substantially as set forth.

3. In a car-seat, the combination of a pair of cross rails, means for supporting the same, comprising a pedestal adjacent the aisle end of said rails, an aisle end plate secured to the ends of said rails, a curved track supported on said rails, inwardly from said end plate, a back, a back-supporting standard having supporting means therefor extending inwardly therefrom, movably mounted on said track, a seat-cushion extending above said track, rocker means supporting the same above said cross rails, a lever mounted on the outer side of said standard, having pin and slot connection therewith, a rock-shaft operated by said lever, and means for operating said rocker means when said rock-shaft is operated, substantially as set forth.

4. In a car-seat, the combination of a pair of cross rails, means for supporting the same, comprising a pedestal adjacent the aisle end of said rails, an aisle end plate secured to the ends of said rails, a curved track supported on said rails, approximately over said pedestal, a seat cushion above said track, a back, of less length than said seat cushion, a standard secured to the end of said back and extending around the end of said seat cushion, rollers extending inwardly from said standard, supported on said track, a rocker supporting said seat, and means for operating said rocker, comprising a lever having a sliding connection with said standard, between said standard and end plate, substantially as set forth.

5. In a car-seat, the combination of a

curved channel track having its flanges directed outwardly, a pair of brackets secured to and supporting said track, adapted to be secured on a pair of cross rails, a bracket centrally secured to the rear surface of the vertical web of said track, and a rocker pivotally secured to said last-named bracket, substantially as set forth. 70

6. In a car-seat, the combination of a pair of cross rails, a curved channel track mounted on the same, a seat-cushion having a frame having a vertical opening in the under side thereof, a rocker supporting one end of said seat, a bracket secured to said track, said bracket and rocker having portions extending upwardly into said opening in the seat-cushion frame, and means for pivotally supporting said rocker from said upwardly extending portion of said bracket, within said seat-cushion frame, substantially as set forth. 75

7. In a car-seat, the combination of a pair of cross rails, a curved channel track mounted on the same, adjacent the aisle end thereof, and facing outwardly, an end plate carried by the ends of said rails, having an inwardly directed top flange, a back-supporting standard between said end plate and track, having rollers mounted on said track, a lever on the outer side of said standard, connected for movement therewith, and beneath the flange of said end plate, and a rock-shaft having an end bearing in said end plate, and operably connected to said lever, substantially as set forth. 85

8. In a car-seat, the combination of a pedestal, a pair of cross rails supported thereby, with their ends overhanging the same, a track supported by said rails, a bracket secured to said track, and a rocker supported from said bracket, said track, bracket and rocker being mounted approximately over said pedestal, and a back-supporting standard movably mounted on said track, substantially as set forth. 90

9. In a car-seat, the combination of a pair of cross rails, a curved channel track mounted on the same, a bracket secured to said track, having an upwardly extending portion, a rocker pivoted to said portion, a standard movably mounted on said track, an eccentric revolvably mounted in the lower part of said rocker, and lever means connecting said standard and eccentric for the operation of the latter when said standard moves, substantially as set forth. 105 110 115

This specification signed and witnessed this 7th day of August, 1915.
